UNITED STATES PATENT OFFICE.

THOMAS S. CRAPP AND ROBERT C. FINCH, OF INDIANAPOLIS, INDIANA,
ASSIGNORS TO FRANK GLESSNER, OF SHELBYVILLE, INDIANA.

PLUNGER FOR BRICK-MACHINES.

SPECIFICATION forming part of Letters Patent No. 762,230, dated June 7, 1904.

Original application filed June 16, 1903, Serial No. 161,164. Divided and this application filed January 12, 1904. Serial No. 188,731.
(No model.)

To all whom it may concern:

Be it known that we, THOMAS S. CRAPP and ROBERT C. FINCH, citizens of the United States, residing at Indianapolis, in the county 5 of Marion and State of Indiana, have invented certain new and useful Improvements in Plungers for Brick-Machines, of which the following is a specification.

This invention relates to improvements in 10 plungers for brick-machines, and is a division of an application for patent for a brick-machine filed by us on the 16th day of June, 1903, Serial No. 161,164.

The object of the invention is to provide a 15 plunger that will allow the clay to pass through it with as little resistance as possible, but only in the direction of the molds.

We accomplish the objects of the invention by the mechanism illustrated in the accompa- 20 nying drawings, in which—

Figure 1 is a horizontal section of the improved plunger taken longitudinally of the machine; Fig. 2, a longitudinal vertical section of same, and Fig. 3 a transverse section 25 on the line 3 3 of Fig. 1.

Like characters of reference indicate like parts throughout the several views of the drawings.

4 is the press-box, 5 the face-plate between 30 the press-box and the molds, and 6 the molds in which the brick are formed.

7 is a journal-box, which is supported by the radial webs 8 at the mouth of the press-box. 9 is a hollow shaft which has a bearing 35 in said journal-box. The ends of the said box are capped with caps 10 10 and suitably packed to prevent the access of clay into the bearings. Passing through the hollow shaft 9 is the piston-rod 11, which terminates within the press- 40 box 4, and to it is secured the plunger 12. This plunger comprises the outer wall or shell

13, having inwardly-beveled edges, so as to present the minimum obstruction when the plunger is forced through the clay, and it has the transverse wall or diaphragm 14, through 45 which are a plurality of openings for the clay to pass through in the movement of the latter toward the molds 6. The piston-rod 11 has an intermittent longitudinally-reciprocating movement, whereby the plunger is recipro- 50 cated. When the plunger is moved toward the molds in the operation of pressing the clay therein, the backward movement of the clay is prevented by the closures or valves 15, which are hinged at their upper ends to the 55 diaphragm, as shown. The lower ends of these valves are made thin, so as to cause them to cut through the clay readily under pressure from the outward movement of the plunger. 60

Having thus fully described our invention, what we claim as new, and wish to secure by Letters Patent, is—

In a press-box for brick-machines, a piston having a tubular periphery with rigid beveled 65 ends, a transverse diaphragm between said ends integral with said periphery, said dia- phragm having transverse openings, and valve- plates hinged at their upper ends so as to swing outwardly to allow the clay to pass, 70 said plates being reduced in thickness toward their free ends to facilitate their passage through the clay.

In witness whereof we have hereunto set our hands and seals, at Indianapolis, Indiana, this 75 29th day of December, A. D. 1903.

THOMAS S. CRAPP. [L. S.]
ROBERT C. FINCH. [L. S.]
